(57) **CLAIM**

The ornamental design for a laser gun with target assembly, as shown and described.

DESCRIPTION

FIG. 1 is a perspective view of a laser gun with target assembly showing my new design;

FIG. 2 is a perspective view thereof of a laser gun of FIG. 1 isolated for clarity;

FIG. 3 is another perspective view thereof;

FIG. 4 is a left view thereof;

FIG. 5 is a right view thereof;

FIG. 6 is a front view thereof;

FIG. 7 is a rear view thereof;

FIG. 8 is a top view thereof;

FIG. 9 is a bottom view thereof;

FIG. 10 is a perspective view thereof of a target of FIG. 1 isolated for clarity;

FIG. 11 is another perspective view thereof;

FIG. 12 is a front view thereof;

FIG. 13 is a rear view thereof;

FIG. 14 is a left view thereof;

FIG. 15 is a right view thereof;

FIG. 16 is a top view thereof; and,

FIG. 17 is a bottom view thereof.

The broken lines shown in the figures are for the purpose of illustrating portions of the laser gun with target assembly, which form no parts of the claimed design.
